(57) **CLAIM**

The ornamental design for a plunger, as shown and described.

DESCRIPTION

FIG. 1 is a front perspective view of a plunger according to an embodiment of the present design;

FIG. 2 is front elevation view of the plunger of FIG. 1; FIG. 3 is a rear elevation view of the plunger of FIG. 1; FIG. 4 is a left side view of the plunger of FIG. 1; FIG. 5 is a right side view of the plunger of FIG. 1; FIG. 6 is a top plan view of the plunger of FIG. 1; FIG. 7 is a bottom plan view of the plunger of FIG. 1; and, FIG. 8 is a cross-sectional view of the plunger of FIG. 1 taken in the plane of and the direction indicated by line 8-8 of FIG. 2, with a cross-sectional view taken in the plane of and in an opposite direction indicated by line 8-8 being a mirror image thereof.

The broken lines in the drawings are for the purpose of illustrating portions of the plunger that form no part of the claimed design. The dot-dash lines in the drawings represent the bounds of the claimed design and form no part thereof.
